(57) **CLAIM**

The ornamental design for a solar collector for landscape light, as shown and described.

DESCRIPTION

FIG. 1 is a left, front and top perspective view of a solar collector for landscape light showing my new design; FIG. 2 is a right, rear and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures illustrate portions of the solar collector for landscape light that form no part of the claimed design.
